UNITED STATES PATENT OFFICE.

CHARLES J. NELSON, OF MADELIA, MINNESOTA, ASSIGNOR OF ONE-HALF TO HERMAN R. ANDERSON, OF MADELIA, MINNESOTA.

DOOR-LATCH.

1,145,788.

Specification of Letters Patent.

Patented July 6, 1915.

Application filed August 21, 1913. Serial No. 786,006.

To all whom it may concern:

Be it known that I, CHARLES J. NELSON, a citizen of the United States, residing at Madelia, in the county of Watonwan and 5 State of Minnesota, have invented new and useful Improvements in Door-Latches, of which the following is a specification.

An object of the invention is to provide a door latch, particularly adaptable for use 10 on barn doors, and wherein a latch is provided which can be conveniently opened from the inside or outside.

The invention embodies, among other features, a door latch of simple and durable 15 construction and in which, when the latch is applied to a barn door, the locking member will lie within the building or structure upon which the door is mounted so that the said locking member will be protected from the 20 inclemencies of the weather.

The invention still further embodies a door latch in which the locking member will engage the keeper to secure the door in a locked position when a sufficient force is exerted on the door to swing the same into 25 closed position, thus permitting of securing the door in a closed position without any further exertion on the part of the operator except to impart to the door a swinging 30 movement sufficient to carry the locking element into engagement with the keeper.

In the further disclosure of the invention reference is to be had to the accompanying drawings, constituting a part of this specification, in which similar characters of reference denote corresponding parts in all the 35 views, and in which:

Figure 1 is a front elevation of the latch; Fig. 2 is a rear elevation; Fig. 3 is a horizontal sectional view taken on the line 3—3 in Fig. 2; Fig. 4 is a vertical sectional view taken on the line 4—4 in Fig. 3; Fig. 5 is a fragmentary vertical sectional view of the front of the latch, showing the manner of securing the operating handles in locked position; and Fig. 6 is a perspective view of the keeper.

Referring more particularly to the views, I disclose a door 10 mounted to swing on a 50 suitable door casing 11, a transverse opening 12 being provided in the door 10 and through which extends a shank 13 mounted to swing on the door at its medial portion and within the opening 12, one end of the shank 13 projecting forwardly beyond the front face of

the door and terminating in an outer handle 14, with the other end of the shank projecting beyond the inner face of the door and having connected thereto an inner handle 15.

A hook-like locking element 16 is rigidly 60 carried on the inner end of the shank 13 and is preferably secured thereto by a plurality of transverse bolts 17, which, passing through the shank and the locking element, not only secure the locking element to the shank, but 65 also pass through the inner handle 15 to rigidly secure the same upon the inner end of the shank. The locking element 16 carries an eye 18 in which is secured one end 70 of a contractile spring 19 having the other end thereof secured to a suitable hook 20 carried on the inner face of the door 10.

A plate 21 is secured to the front face of the door 10 and includes a vertically slotted stop member 22, having the slot thereof registering with the opening 12 in the door, the said shank 13 being adapted to loosely pass through the vertical slot of the stop member, as shown, so that when the outer handle 14 is pressed downwardly, the downward 80 movement of the said handle and shank will be limited by the stop member 22 having a wall thereof adapted to be engaged by the shank, the upward movement of the handle and shank being also limited by the shank 85 engaging the opposite wall of the stop member when the door is in a locked position.

A keeper 23 is secured to the inner face of the door casing 11 and includes a plate 24 provided with slots 25 through which are 90 passed suitable screws 26 for supporting the keeper on the door casing, it being readily understood that the heads of the screws are larger than the width of the slots in the plate 24, thus permitting of adjusting the 95 keeper vertically on the door casing to compensate for any sagging of the door relatively to the door casing. As mentioned heretofore, the locking element 16 is preferably of a hook-like nature and includes 100 a beveled face 27. Now when the door is in an open position and it is desired to close the same relatively to the door casing and secure the door in closed position, it is only necessary to impart a swinging movement to the door sufficient to bring the locking element 16 into engagement with the keeper 23. When this occurs the beveled face 27 of the locking element will engage 105 one of a plurality of projections 28 of the 110

keeper and ride over the said projections, whereupon the action of the spring 19 exerting a downward pull on the locking element, will force the hook end thereof into a recess 5 29 formed between the projections 28 of the keeper, thus securing the door in closed and locked position. By simply pressing downwardly on the outer handle 14 the inner end of the shank 13 will be swung upwardly to 10 disengage the locking element from the keeper to unlock the door from the outside and similarly, when it is desired to open the door from the inside, it is only necessary to pull upwardly on the inner handle to disengage the locking element from the keeper, as will be readily understood by referring 15 to the views.

A plurality of horizontally registering apertures 30 are formed on the side walls 20 of the side member 22 and lie beneath the normal horizontal plane of the shank 13. Now when it is desired to lock the shank in an inoperative position, the curved shank 31 of a padlock 32 is passed through the 25 horizontally alining apertures 30 and the shank locked to the body of the padlock, thus causing the shank 31 of the padlock to restrict the movement of the shank 13 carrying the inner and outer handles and holding 30 the shank 13 in an inoperative position so that the slight movement of the shank will be insufficient to disengage the locking element from the keeper, thus retaining the door in a locked position and preventing 35 thieves or burglars from opening the door and entering the building on which the door swings.

From the foregoing description it will be 40 apparent that my device is of a simple and durable construction and in which all of the parts except the outer handle are protected from the inclemencies of the weather, the keeper of the door casing and the locking element for engagement with the keeper be-

ing arranged to lie within the building upon 45 which the door is mounted to swing.

In order to secure the door in an open position after the same has been unlocked and swung open, a suitable securing member 33 is supported on the casing 11 to be engaged 50 by the handle 14 as the door swings backwardly upon the casing, thus retaining and locking the door in an open position.

Having thus described my invention, I 55 claim:

A door latch comprising a hollow member carried by the door and extending therethrough, a shank extending through the member and pivoted therein and having its inner end extending beyond the inner side 60 of the door, a handle carried by the inner end of the shank and lying to one side thereof, an angular shaped locking element located at the inner end of the shank and having one of its sides detachably secured to 65 the inner end of the shank at a point opposite the point of connection between the shank and the handle, means extending through the mentioned side of the locking element and through the shank and handle for securing the locking element and handle to the shank, the said locking element having its other side extending downwardly below 70 the shank, a keeper mounted on the door frame and adapted to receive the downwardly extending side of the locking element when the door is in closed position, and a spring having one end secured to the 75 under side of the first mentioned side of the locking element and having its opposite end extending downwardly and secured to the door, for the purpose specified.

In testimony whereof I affix my signature in presence of two witnesses.

CHARLES J. NELSON.
